UNITED STATES PATENT OFFICE.

HERBERT JAMES SIMPSON, OF NORTON-ON-TEES, ENGLAND.

MECHANICAL STARTER FOR INTERNAL-COMBUSTION ENGINES.

1,375,472.

Specification of Letters Patent. Patented Apr. 19, 1921.

Application filed July 31, 1920. Serial No. 400,564.

To all whom it may concern:

Be it known that I, HERBERT JAMES SIMPSON, of 23 Grange road, Norton-on-Tees, in the county of Durham, England, a subject 5 of the King of Great Britain and Ireland, have invented certain new and useful Improvements in Mechanical Starters for Internal-Combustion Engines, of which the following is a specification.

10 This invention relates to mechanical starters for internal combustion engines, more particularly of motor driven vehicles and has for its object to provide apparatus of this kind adapted to convert a rectilinear motion into a rotary motion for starting the vehicle or the like by means of a hand lever or pedal lever actuated by the driver from his seat in the vehicle or the like.

The invention consists in the improved 20 mechanical starting apparatus for internal combustion engines, more particularly of motor driven vehicles, comprising a starting drum or cylinder, rotatably mounted within a casing and geared to the engine shaft, provided with one or more double endless spiral 25 grooves in which pins engage, each pin being secured to one end of an operating rod having a rectilinear motion in suitable guides within and parallel to the longitudinal 30 axis of the casing, the other end of the rod being linked by a connecting rod or the like to a starting lever adapted for manual or pedal operation.

The chief advantage of the present invention lies in the fact that the rotation of the drum is always in the same direction whether the starting lever be moved forward or backward, this feature being obtained by the use of the above mentioned double endless spiral grooves.

In order that the nature of the invention may be clearly understood the preferred form of the improved starting apparatus will now be described with the aid of the 45 accompanying drawings in which Figure 1 is a side view of the apparatus connected up to a starting lever; Fig. 2 is a plan view of the apparatus shown in Fig. 1, the cover being removed and the connection to the 50 starting lever omitted; Fig. 3 is a side view of the grooved drum shown in Fig. 2 looking in the direction of the arrow III.

Fig. 4 is an elevation and Fig. 5 a part section of a modified construction.

55 Referring to Figs. 1, 2 and 3 of the draw-

ings, the apparatus shown comprises a cylindrical casing 1 in which is mounted a drum or cylinder 2, the shaft 3 of which rests in suitable bearings 4, 5, at the ends of the casing 1, the drum shaft 3 being provided at each end with collars 6 and ball bearings 7 to take the thrust of the drum. The surface of the drum 2 is slotted to form double endless spiral grooves crossing each other and running in opposite directions 60 around the drum. Two such endless spiral grooves 8, 9, are shown. Each groove makes a half revolution in the whole length of the drum and completes the revolution by returning on the opposite side of the drum to 70 its starting point.

The casing 1 is provided with a cover 10, the space between the casing and the cover forming rectilinear guides 11 in which slide crossheads 12, 13, attached to two rods 14, 15, one on either side of the drum 2. Attached to or forming part of these crossheads are pins 16, 17, which respectively engage in the spiral grooves 8, 9, of the drum 80 as shown.

When the pin 17, for example, moves forward along its groove 9, the drum 2 is rotated until the pin 17 reaches the farthest point of the groove. The pin then will have rotated the drum 2 through half a 85 revolution. On being moved backward the pin 17 still moves in its own groove 9, but in the section of the groove on the opposite side of the drum (Fig. 3), thus returning to its starting point in the groove and causing the drum 2 to rotate in the same direction as before (Figs. 2 and 3).

As shown, the rods 14, 15, slide through stuffing boxes 25, 26, and are connected by a cross bar 18 having lugs 19, 20, pierced 95 with a hole to take a pin 22 securing the connecting rod 21 which is also pivotally connected to the starting lever 23. At the other end of the drum 2 a ratchet wheel 24 is provided co-acting with a pawl 28, while 100 a sprocket wheel 27 is secured upon the shaft 3 and gears with another sprocket wheel on the engine shaft by means of a chain (not shown).

When the starting lever 23 is pulled over 105 into the dotted line position the drum 2 is rotated half a revolution as described above: if this is found not sufficient to start the engine or motor, the lever 23 is pushed back again causing the drum to rotate a fur- 110

ther half revolution in the same direction as before, thus providing a continuous rotary motion.

The rotary motion of the drum shaft 3 is transmitted by the sprocket wheel 27 which acts as a free wheel, that is, revolves freely in one direction only, by an endless chain to the sprocket wheel fixed on the engine or motor shaft.

10 In the arrangement shown in Figs. 4 and 5 only a single groove 9 is provided in the drum 2 and the pin 17 engaging in the groove is carried by a sliding plate 14 which is connected to the starting lever as 15 before.

It is evident that various modifications might be made in the details of the apparatus described above and illustrated in the drawing without in any way altering the essential character of the apparatus.

20 What I claim and desire to secure by Letters Patent is:—

A manually operated starting apparatus for internal combustion engines, comprising, in combination, a cylindrical casing provided with a longitudinal slot, a thrust

bearing at each end of said casing, a rotary drum journaled therein, a ratchet wheel at one end of said drum, an endless inclined groove formed in the surface of the 30 drum proceeding from a point near one end of the drum and coinciding with one end of a cross-sectional diameter of the same along one side of the drum to a point near the other end of the latter coinciding with the 35 opposite end of said diameter, returning along the opposite side of the drum to the first-mentioned point, a reciprocating member supported near one side of the casing and parallel to the axis of the drum, a projection upon said member engaging in the endless groove in the drum and working on said groove in the casing, a pawl within the casing adapted to engage the said ratchet to permit rotary movement in one 40 direction only, manually operated means for reciprocating said member and means for transmitting the rotation of the drum to an engine shaft.

45 In testimony whereof I have signed my name to this specification.

HERBERT JAMES SIMPSON.
